UNITED STATES PATENT OFFICE.

WALLACE PRATT GROOM, OF NEW YORK, N. Y.

SYSTEM OF VENTILATING RAILWAY TUNNELS OR SUBWAYS.

No. 832,856.

Specification of Letters Patent.

Patented Oct. 9, 1906.

Application filed September 7, 1905. Serial No. 277,282.

To all whom it may concern:

Be it known that I, WALLACE PRATT GROOM, a citizen of the United States, and a resident of Brooklyn borough, New York, in the county of Kings and State of New York, have invented certain new and useful Improvements in Systems of Ventilating Railway Tunnels or Subways, of which the following is a specification.

10 My invention relates to systems and appliances for ventilating railway subways and tunnels; and it has for its object to so construct and arrange flues or ducts for influx of fresh and pure air and for efflux of spent or vitiated air and to so construct and attach appliances to a car of any train to be run through such tunnel or subway and also such appliances to the tunnel or subway itself as to cause the movement of trains therein to aid and increase the influx of fresh air to and efflux of vitiated air from such tunnel or subway, which influx and efflux will take place at all times, even in intervals when movement of trains therein is intermittent. The 25 terms "subway" and "tunnel" are herein used as signifying substantially the same thing.

My invention partly consists in a peculiar arrangement and construction of air ducts or flues for inflow and outflow of air to and from a subway or tunnel.

The invention also consists in appliances for substantially dividing the space in a tunnel or subway into distinct longitudinal passages for the circulation of air therein longitudinally in sections where the ventilating ducts or flues are located in relation with said space.

The invention further consists in the attachment of wings or fans to a car of each train which passes through such tunnels or subways or which ply therein, whereby the movement of air by the motion of the train is increased and intensified, and also, as part 45 of the general system, in the special construction and means of attachment of such wings or fans to a car or cars.

Figure 1 of the drawings represents a vertical longitudinal section of a subway embodying my system of and appliances for ventilation, the section being on line $x-x$ in Fig. 2. Fig. 2 is a plan of the same with a portion of the superimposed earth and a portion of the roof removed. Fig. 3 is a partial cross-section made on line $y-y$ in Fig. 1. Fig. 4 is a detail showing means employed

for dividing the tunnel longitudinally into distinct passages for air. Figs. 5, 6, and 7 are respectively a side elevation, a front elevation, and a plan of a spring-hinge attachment, whereby the wings or fans hereinlater described may be fastened in working position on a car. Fig. 8 is an enlarged view of a wing or fan, showing a method of attaching the same to the spring and to a car. 65

The tunnel or subway A, Figs. 1, 2, and 3, is shown in these drawings as constructed with a sheathing of metal B on the under side of its roof and metal sheathing B' on the inner surface of its sides, the roof being supported by vertical metal posts a and girders b , the tunnel having parallel railway-tracks therein, the rails being shown at c supported on ties d . 70

A car C is shown in side elevation in Fig. 1, in plan in Fig. 2, and in front elevation in Fig. 3, its direction of running (indicated by darts in Fig. 2) being from left toward the right in the drawing, and the movement of the car being always in the same direction 80 for any one track. 75

The construction of the car may be of any type, either adapted to electric propulsion or propelled by any kind of power while passing through the tunnel or subway, and the 85 construction of the tunnel may be of any kind other than that shown—as an excavation through solid rock, a mason-work structure, &c.—for, although the action of my invention is partially dependent upon a tunnel or subway and a car or train of cars running therein, it is wholly independent of any particular type of tunnel or car except that the front end of the car is assumed to be closed, as shown in Fig. 3. 90

I have shown the tunnel or subway as containing two parallel or substantially parallel railway-tracks; but my invention is entirely independent of the number of tracks and is adapted to use in a tunnel wherein only a 100 single track is employed or in a subway having any practicable number of tracks. 95

Extending to a considerable distance rearward relatively to the direction in which the car uniformly runs is a duct E for outflow of 105 vitiated air from the interior of the subway. Extending forward to a considerable distance relatively to the direction in which the car uniformly runs is a duct F for inflow of 110 fresh cooler air. It is found by experience that for much of the time when a subway is used for passenger traffic the air there is

uniformly of higher mean temperature than that of the exterior atmosphere. This being the case, an outflowing current of spent or vitiated air and an inflowing current of fresh cooler exterior air may be set up and maintained by the supply of properly-constructed air-ducts, the currents being generated by the different specific gravities of the cooler and warmer air, and the arrangement and construction of the ducts E and F are such as will not only render the action of the air-currents so set up to be as vigorous as is possible in air-currents created by such differences of temperature, but also will greatly accelerate 15 outflow of vitiated air and inflow of fresh air through force generated by motion of a car or train of cars approaching the open mouth of the vitiated-air duct and again rapidly moving away from the mouth of the fresh-air duct, as will be more fully explained hereinafter.

In the drawings the portion of the air-ducts contained in the tunnel or subway are shown as extending downward at the side of 25 the track nearly to the bottom or floor of the subway, with easy bends where they pass up through the sheathing B, from which they extend upward through the superimposed earth G to an elevation sufficient to establish 30 a positive upward current in the vitiated-air duct and a positive downward current in the fresh-air duct, the currents within limits being stronger proportionately to the said elevation, as is the case with ordinary furnace-chimneys. As the differences of temperature establishing the currents are small in comparison with the ordinary differences of temperature which induce the draft of furnace-chimneys, the flow of air in the 35 ventilating-ducts E and F will at best be sluggish as compared with ordinary furnace-draft, but will be much accelerated by the movement of the car or train of cars when the latter are passing at the usual speed through the 40 subway, as more fully hereinafter explained.

The vitiated-air duct and the fresh-air duct may be placed at different points; but I prefer to bring them close together and from where they pass up through the sheathing to 45 contract them longitudinally and widen them laterally with respect to the direction of the tunnel, as shown in section and plan, in such manner as to merge them into a single stack H above the ground G, the partition d, Fig. 1, 50 separating the fresh-air duct E from duct F, and to extend the duct E to an elevation considerably higher than the top of the fresh-air duct, as clearly indicated in the drawings. The practicable height of each of these ducts 55 will depend more or less upon conditions of practice; but the fresh-air duct should wherever possible rise to a point which is comparatively free from dust, and the vitiated-air duct should extend to a point considerably higher, not only for strengthening

the current therein, but for discharging the vitiated air at a point which will practically exclude the possibility of any intermingling of the discharged air and that entering the cold-air duct. Both ducts should be provided with suitable hoods for preventing the entrance of rain and snow. These hoods are indicated at h and h', Fig. 1.

By reference to Figs. 1 and 3 it will be seen that the mouths m of the ducts are in this example of my invention oblong in contour, the object sought being to obtain as much area of opening as possible within the subway, and in the construction of the ducts shown in Figs. 2 and 3, where they merge 80 into the stack H, the object is to avoid contracting the cross-section area of the duct as much as practicable in order to secure as large a volume of flow as practicable into or out of the mouths m of said ducts.

As the car or train of cars approach at speed toward the mouth of duct E they generate pressure in the tunnel in advance of their progress, setting up a strong current in the direction of their motion. A portion of this 90 current presses against the open mouth of duct E, enters the duct, and materially accelerates the upward flow of air through said duct. Conversely, the current ahead of the car or cars blowing over and not into the 95 mouth of the fresh-air duct F in the tunnel produces a partial vacuum in this duct, and this accelerates the flow through the duct into the subway. This action is based on the long-recognized fact that a forcible current 100 of air blown along over the outer walls of a tube or air-duct in the direction of its length and passing over an open end of the tube, while its other end is not subjected to the action of the outer current, produces a flow 105 of air in the tube in the direction of the outer current. Also after the car or train of cars have passed the ventilating-ducts the pressure is materially lessened in the tunnel immediately behind and to a considerable distance 110 in the rear of the train. The exterior air then taking the path of least resistance—to wit, the shorter fresh-air duct—therefore continues to flow into the subway after the 115 passage of the train. The action explained thus augments the flow, which in absence of the movement of cars in the subway would be established by temperature differences and resulting specific-gravity differences only.

It is obvious that the action described will be more pronounced the more nearly it can be confined to a single and distinct longitudinal passage in a subway. Where such a tunnel contains more than one parallel track 125 and posts a are ranged at set distances between the tracks, it will be necessary in order to insure best results to interpose a septum between each two adjacent posts for a considerable distance on each side of the venti- 130

lating-stack H. I interpose between the posts a curtains K, Fig. 4, of flexible material, such curtains being mounted on rollers k after the manner in which window-shades are mounted, said curtains being weighted at the lower margin by a bar k' or otherwise secured at the bottom to hold them in substantially vertical position when pulled down, as shown in Fig. 4; but I make no claim herein for such septum or equivalent device, reserving my claim thereto as the subject-matter of a separate application. It is obvious, also, that the lower parts of the air-ducts E and F may be varied in shape to adapt them to tunnels or subways of different cross-sections, widths, and depths; but whatever available space the parts of these ducts contained in the tunnel or subway may occupy it is essential that the mouths of those parts of the vitiated-air ducts in the tunnel shall face toward and the mouths of those parts of the fresh-air ducts in the tunnel shall face away from approaching cars. It will also be apparent that the effective production of increased pressure in advance of moving cars in the tunnel will be favored by making the front surfaces of the leading cars of trains conform in shape as closely as practicable to the shape of the cross-section of the tunnel; but any car already built and in use can be made to effect the same purpose in a subway supplied with parts of my invention already described by the attachment to such car of wings or fans L, Figs. 3 and 8, which act in combination with the ventilating-ducts E and F, placed at suitable intervals throughout the length of the tunnel. In practice the intervals can seldom be made uniform; but they should be as uniform as existing conditions will permit.

I will now describe means for movably and detachably fastening the wings or fans to the car. Although the body of the fan L, Fig. 8, is there shown in face view to be of rectangular contour, it may have any contour which is required to enable a set of these fans to fill the larger part of the sectional space between the car and the inner surfaces of the tunnel.

The bodies of the fans made be made of thin sheet metal or cloth stretched over a light wire frame or paper glued upon a skeleton of bamboo after the manner of Japanese fans or of any other material whatever which combines sufficient strength with lightness and resilience and is sufficiently impervious to the passage of air through the texture thereof. The fan-bodies may be each provided with a shank n for attachment to a spring-hinge p of special construction, yet to be described, in such manner that their faces stand normally at right angles with the vertical sides of the car. The spring-hinge attachment is preferable, as it enables the body of the fan to pass easily

any obstructions while the car is moving should any object temporarily constitute an obstruction; but this kind of attachment is not essential to the general operation of the wings or fans, which by preventing a large part of the rearward slip of air past the car produce a stronger pressure and flow of air in advance, as well as a greater reduction in pressure in the rear thereof.

The spring-hinge I prefer to employ is shown in detail in Figs. 5, 6, and 7. It is composed of a furcated metal piece q, which has a socket v at the top for reception of the shank n, riveted or otherwise suitably fastened to the margin of the body L of the fan, as shown in Fig. 8. Said socket v is provided with a set-screw v' for clamping shank n fast when inserted in the socket. The body of the fan may thus be attached to or detached from the spring-hinge without removing the latter from its permanent attachment, hereinafter described. In the recess s is fitted under the clamping-block t the upper end of a flat spring s', which is firmly clamped and held by a rivet s'', which passes through q, s', and t. The lower end of s' is formed into a cylindrical loop which reaches to and bears upon the surface of that part of the bracket or foot-piece t'' which lies between the furcations of the piece q. The normal relative positions of the parts are shown in full outline in Figs. 5 and 6, the normal position of spring s' being shown partly in dotted outline in Fig. 5. When the furcated piece q is turned on its pivot t' toward the left, as shown in dotted outline in Fig. 5, the spring is bent as shown, and its resilience forces q back into normal position when q is left free to move. A corresponding action of the spring takes place when q is turned on its pivot toward the right. Thus the spring s' acts to restore q to its normal relative position—that is to say, to a position at right angles with the foot-piece t''—whenever q and its socket v are swung from a line vertical to the foot-piece, and they hold a fan L with its shank n inserted and clamped in said socket, as shown in Fig. 8, in such position whenever the movement of the fan is not resisted by temporary obstruction in addition to the resistance of air against its face, the spring being of a strength to hold the body of the fan in position without material deflection when the car carrying it is in motion at normal speed.

Near the front platform of the car or elsewhere, as convenient, bars W, Figs. 1, 2, and 3, of suitable material, either wood or metal, are secured to the body of the car, and to these the foot-pieces t'' of the spring-hinges are attached.

The station-platforms of a subway extend laterally out toward the track, so as to leave very little space between their outer margins and car-platforms standing adjacent

thereto, as shown at R, Fig. 3, where R represents a section of a station-platform whereon passengers walk to the car-platform R'. Contact of the wings or fans with the projecting edge of such station-platforms is prevented by leaving a space between the fan below the level of the station-platform and the fan above said level, as clearly shown in Fig. 3:

10. To regulate the inflow of cold air in very cold weather and to prevent the tunnel from becoming uncomfortably cold, I place a damper D, Figs. 1 and 2, in the fresh-air duct.

15. What I claim as my invention, and desire to secure by Letters Patent, is as follows:

1. The combination with a subway or railway tunnel containing a railway-track, of a discharge air-duct and an air-supply duct, the openings of said ducts in said subway or tunnel facing in opposite directions, the air-supply duct facing toward the direction in which cars or trains are designed to run in said subway or tunnel, substantially as described and for purposes specified.

2. The combination with a subway or railway tunnel containing a railway-track, of a discharge air-duct, and an air-supply duct, the openings of said ducts in said subway or tunnel facing in opposite directions, the air-supply duct facing toward the direction in which cars or trains are designed to run in said subway or tunnel, and the ducts being extended up through the roof of the subway or tunnel, substantially as and for the purposes set forth.

3. The combination with a railway subway or tunnel containing a railway-track, of a fresh-air duct and a vitiated-air duct, the openings of said ducts within the subway or tunnel facing in opposite directions, the air-supply duct facing in the direction the cars are designed to run in said subway or tunnel, and the ducts being extended up through the roof of said tunnel, the vitiated-air duct being extended up to a greater height than the air-supply duct, substantially as described.

4. The combination with a subway or railway-tunnel, containing a railway-track, and

a car or cars, of a fresh-air-supply duct, and 50 a vitiated-air-discharge duct, both ducts having openings within said subway or tunnel, said openings facing in opposite directions, the opening of the fresh-air-supply duct, facing toward the direction cars are designed to 55 run in said subway or tunnel, and both ducts above the subway or tunnel being merged into a single stack, substantially as and for the purposes specified.

5. As part of a system of ventilation for 60 railway tunnels or subways, containing one or more railway-tracks, and cars designed for running in specific direction or directions, on said track or tracks, said tunnel being provided with a fresh-air-supply duct, having 65 within said tunnel an opening facing toward the direction in which the car or train of cars is designed to run, on any contained track, and provided with a vitiated-air-discharge duct, having within said tunnel or subway an 70 opening facing in an opposite direction from that in which the opening of said supply-duct faces, of a set of wings or fans attached to, and extending laterally from, the body of a car designed to run in said railway tunnel or 75 subway, substantially as and for the purposes described.

6. The combination with a railway subway or tunnel, containing a railway-track, of a 80 fresh-air duct and a vitiated-air duct, the openings of said ducts within the subway or tunnel facing in opposite directions, the air-supply duct facing in the direction cars are designed to run in said subway or tunnel, and the ducts being extended up through the roof 85 of said tunnel, the vitiated-air duct being extended up to a greater height than the air-supply duct, and the fresh-air duct containing a damper, substantially as and for the purposes set forth.

90 Signed at Brooklyn, (New York city,) in the county of Kings and State of New York, this 28th day of August, A. D. 1905.
